WEB PRINTING ROTARY PRESS

Filed June 10, 1931

UNITED STATES PATENT OFFICE

HOWARD M. BARBER, OF PAWCATUCK, CONNECTICUT, ASSIGNOR TO C. B. COTTRELL & SONS COMPANY, OF WESTERLY, RHODE ISLAND, A CORPORATION OF DELAWARE

WEB PRINTING ROTARY PRESS

Application filed June 10, 1931. Serial No. 543,288.

The object of my invention is to provide novel means for printing successively on the web with predetermined spacings between the impressions within the range of the press.

5 My invention generally comprises alternately acting web advancing means operable to pass the web through the printing couple at the surface speed thereof during the printings and at the same or lesser speeds between 10 the printings, according to the required spacings between the impressions.

My invention more particularly comprises alternately acting web advancing units located respectively on the delivery and feeding- 15 sides of the printing couple for controlling the passage of the web therethrough; the web advancing unit on the delivery side of the printing couple being driven by the printing couple at the surface speed thereof and the web advancing unit on the feeding-in side of the printing couple having a variable speed drive therefor to permit said unit to be driven at the same surface speed as the printing couple or at lesser speeds.

25 My invention also includes a change gear drive for the web supply and take-up units, the web supply units serving to drive the web advancing unit on the feeding-in side of the printing couple through the above mentioned 30 variable speed drive.

A practical embodiment of my invention is represented in the accompanying drawing, in which:

Fig. 1 represents a diagrammatic side 35 elevation of so much of a web printing rotary press as will give a clear understanding of my invention; the parts being shown in the positions they assume just before the web advancing unit on the feeding-in side of the 40 printing couple releases control of the web and just before the web advancing unit on the delivery side of the printing couple takes control of the web to pass it through the printing couple at the surface speed thereof 45 during the printing operation;

Fig. 2 represents a diagrammatic detail top plan view of the cam mechanism for controlling the alternate action of the drop rolls of the web advancing units; and

50 Fig. 3 represents a diagrammatic top plan

view of the variable speed drive for the web advancing unit on the feeding-in side of the printing couple.

The form and impression cylinders of the web printing couple are denoted by 1 and 2 respectively, the form cylinder in this instance being shown as twice the diameter of the impression cylinder and as having a circumference equal to the combined maximum length of form and spacing of which the press is capable so that it makes one revolution for each impression and spacing.

A suitable inking mechanism 3 is provided for the form 4 on the cylinder 1.

The form and impression cylinders may be 45 driven at a constant speed from the main drive shaft 5 through the train of gears 6, 7 and 8.

The web is denoted by 9, its supply roll by 10 and its re-wound roll by 11. The web supply unit is shown as comprising the web feeding rolls 12, 13 and 14. The web take-up or re-winding unit is shown as comprising the rolls 15, 16 and 17. These two units are driven at selected speeds, according to the 70 form spacings, from the gear 18 on the main drive shaft 5 through the change gear 19 and the gears 20, 21 and 22; the roll 13 of the web supply unit being driven from the gear 22 through the gear 23, shaft 24 and gears 25, 26, while the roll 17 of the web take-up unit is driven from the gear 22 through the gear 27, shaft 28 and gears 29, 30.

Alternately acting web advancing units are provided on the opposite sides of the 85 printing couple. The web advancing unit on the feeding-in side of the printing couple comprises a web feed roll 31 and its coacting drop roll 32. The roll 31 is driven at the required speed to control the spacing lengths, 90 from the web supply unit, through a variable speed drive either at the surface speed of the printing couple or at predetermined lesser surface speeds, according to the spacing lengths required between the impressions. 95 In the present instance the variable speed drive is shown as the well known "Reeves" drive, its pulley 33 being driven through a belt 34 from the pulley 35 on the shaft of the web feed roll 14. The pulley 36 on the shaft 100

of the roll 31 is driven by a belt 37 from the pulley 38 of the said variable speed drive.

- The drop roll 32 is brought into coaction with its web feed roll 31 at the proper time to control the passage of the web through the printing couple during the spacing periods between the printings. In the present instance it is mounted on one arm 39 of a bell crank lever, the other arm 40 of which is provided with a rod 41 which carries a stud or roller 42 traveling in a box cam 43 on a cam shaft 44, which shaft is driven from the shaft of the impression cylinder 2, through the gears 45, 46.
- 15 The web advancing unit on the delivery side of the printing couple comprises a web feed roll 47 and its coacting drop roll 48. The web feed roll 47 is driven at all times at the surface speed of the printing couple from the impression cylinder gear 7, through the gears 49, 50.

- The drop roll 48 is brought into coaction with its web feed roll 47 at the proper times to pass the web through the printing couple 25 at the surface speed thereof during the printing periods. In the present instance this drop roll 48 is mounted on one arm 51 of a bell crank lever, the other arm 52 of which is provided with a rod 53 which carries a stud or roller 54 traveling in a box cam 55 on the cam shaft 44. A tension device 56 of any well known or approved form is provided for the web as it passes to the re-winding roll.

- It is to be understood that the web travels 35 at the same surface speed as the form and impression cylinders during the printings whether the spacings be longer or shorter and also that when the maximum spacings are being used the web also travels at the same surface speed as the form and impression cylinders at all times. However, when shorter spacings between the impressions on the web are required the relative speeds of the rolls in the web supply unit and the rolls in the 40 web advancing unit at the feeding-in side of the printing couple are such as to cause the web to accumulate between the said units when the rolls 31 and 32 have control of the web, in an amount sufficient to permit the 45 speed of the web to be accelerated by the coaction of the rolls 47 and 48 and passed through the printing couple at the surface speed thereof during the printings.

- The drop rolls 32 and 48 of the two web advancing units are alternately lifted by their respective cams 43 and 55 so that the rolls 31 and 32 of the web advancing unit on the feeding-in side of the printing couple are caused to release the web as the rolls 47 and 48 of the 50 web advancing unit on the delivery side of the printing couple take control thereof, and vice versa.

From the above description it will be seen that the web advancing rolls 31 and 32 are 55 caused to travel at a predetermined surface

speed which is slower than that of the rolls 12, 13 and 14 on all except the maximum spacings for which the press is designed. Therefore, the means for controlling the passage of the web through the printing couple causes the 70 web to travel with the form and impression cylinders during the successive printings of the web at the same speed where the maximum spacings are required. Where lesser spacings are required the speed of the web 75 is retarded between the printings, the surface speed of the web advancing rolls 31 and 32 being adjusted by the variable speed drive to suit the required lesser spacing lengths between the impressions. It will be understood 80 that the rolls 47 and 48 of the web advancing unit at the delivery side of the printing couple are always driven at the same surface speed as the printing couple.

It will also be seen that the surface speeds 85 of the web supply unit rolls and the web take-up unit rolls may be adjusted for each form spacing as required, by the change gear drive therefor, the take-up rolls being driven at a speed which will ensure a perfectly wound 90 roll when the web is placed under the proper tension by the tension device 56.

It is evident that various changes may be resorted to in the construction, form and arrangement of the several parts without departing from the spirit and scope of my invention, and hence I do not intend to be limited to the particular embodiment herein shown and described, but

What I claim is:—

1. In a web printing rotary press, a printing couple driven at a constant speed, and alternately acting web advancing units for passing the web through the printing couple at the surface speed thereof during the printings and at the same or lesser speeds between the printings, according to the required spacings between the impressions.

2. In a web printing rotary press, a printing couple driven at a constant speed, the 110 form cylinder having a circumference equal to the combined maximum length of form and spacing, and alternately acting web advancing units for passing the web through the printing couple at the surface speed thereof during the printings and at the same or lesser speeds between the printings, according to the required spacings between the impressions.

3. In a web printing rotary press, a printing couple driven at a constant speed, and alternately acting cam controlled web advancing units for passing the web through the printing couple at the surface speed thereof during the printings and at the same or lesser speeds between the printings, according to the required spacings between the impressions.

4. In a web printing rotary press, a printing couple driven at a constant speed, the 130

the printing couple between the printings, and a variable speed unit driven by the web supply unit for driving the second web advancing unit at the same surface speed as or at lesser surface speeds than the printing couple, according to the required spacings between the impressions.

15. In a web printing rotary press, a printing couple driven at a constant speed, web supply and take-up units, means including a change gear for driving them at predetermined speeds, a web advancing unit driven at the surface speed of the printing couple for passing the web therethrough during the printings, a second web advancing unit for passing the web through the printing couple between the printings, and a variable speed unit driven by the web supply unit for driving the second web advancing unit at the same surface speed as or at lesser surface speeds than the printing couple, according to the required spacings between the impressions.

16. In a web printing rotary press, a printing couple driven at a constant speed, the form cylinder of the printing couple having a circumference equal to the combined maximum length of form and spacing, web supply and take-up units, means including a change gear for driving them at predetermined speeds, a web advancing unit driven at the surface speed of the printing couple for passing the web therethrough during the printings, a second web advancing unit for passing the web through the printing couple between the printings, and a variable speed unit driven by the web supply unit for driving the second web advancing unit at the same surface speed as or at lesser surface speeds than the printing couple, according to the required spacings between the impressions.

In testimony, that I claim the foregoing as my invention, I have signed my name this 45 9th day of June, 1931.

HOWARD M. BARBER.
